EARL H. FOLEY, OF SEATTLE, WASHINGTON, ASSIGNOR TO FILMTONE CORPORATION,
A CORPORATION OF DELAWARE

SOUND RECORDING DEVICE

Application filed August 15, 1924, Serial No. 732,225. Renewed September 23, 1931.

My invention has reference, in its broad aspect, to improvements in methods and apparatus for recording sound of the type exemplified by multiple amplification of the fluctuations induced by sound waves acting through a suitable medium such as a microphone, radio receiving apparatus, or the like, upon an electrical current. To this end, I have uniquely arranged multiple amplifying apparatus of a conventional type in an electrical circuit between a conventional receiving medium such as a microphone, radio receiving set, or the like, and a novel and greatly improved recording device, whereby the minute variations in the electrical current of low amperage induced by the action of the sound waves on the receiving medium are accurately and precisely preserved although the strength of the current is stepped up sufficiently to cause my recording device to function with the required force and precision to accurately produce a permanent record upon a film of material having a degree of hardness heretofore believed to be inapt for use with devices of this character.

My recording device per se, which is the principal element of my present invention and includes an improved stylus assembly, is designed to accurately and precisely engrave by means of said stylus a record of the fluctuations (however minute) in the electric current of my system upon a tape record of any desired hardness varying from the ordinary celluloid tape record to a steel tape record. Furthermore, I have provided unique means whereby the response of the armature of my recording device to the action of the magnetic field may be regulated to compensate for any additional load placed upon the armature in impelling the stylus arm. The stylus arm is also provided with means in the form of a novel plural adjustment to cause the same to dispose the stylus at the most effective angle with respect to the record. My recording device per se also possesses other advantages among which may be mentioned its compactness and simplicity which lends to the improbability of its coming out of order or broken, and the parts

thereof may be readily disassembled for replacement.

It is particularly emphasized that my sound amplifying and recording device is peculiarly adapted for the production of records to be used for so-called talking motion pictures. It has been found almost impossible to synchronize the usual disk record with the strip film used in a cinematograph, while tape records are, in theory, quite satisfactory. However, with sound recording devices heretofore used the power impulse afforded by the fluctuating current of electricity has been found to be too feeble to produce an accurate record on any but record tapes made of the softest substances. These tapes are therefore impractical. My device, on the other hand, is open to none of these objections and has been found in practice to be ideal for the purpose inasmuch as it produces an accurate record on a hard tape of great durability which may be readily synchronized with a motion picture film.

While certain of the principal advantages of my method and apparatus for recording sound have been pointed out above in contrast with the ends attained by such methods and apparatus now in use, it is also emphasized that other objects and advantages are attributable to my invention, and it is believed that these will be readily apparent as the nature and construction of my apparatus is more completely defined.

To these and other ends my invention consists in the construction, arrangement and combination of parts described hereinafter in detail, illustrated in the drawings, and pointed out in the claims forming a part of this specification.

One embodiment of my invention is represented by way of example in the accompanying drawings, wherein:—

Figure 1 is a perspective view of my sound recording device per se, with the top cover plate removed, and one section of the core broken away to more clearly display some of its details,

Figure 2 is a simple diagram of my system of amplification,

Figure 3 is a vertical section of my recording device per se, and

Figure 4 is an enlarged detail of the stylus arm assembly.

Like characters of reference are used to designate like or similar parts throughout the several views of the drawings.

Before introducing the elements of my system of amplification it is pointed out that in 10 each instance a conventional amplifying unit of the audio-frequency tube type is utilized, and that where the system is served from a lighting or other similar circuit the usual rectifying tubes are employed. Referring now 15 particularly to Figure 2 wherein is diagrammatically illustrated my system of amplification it will be seen that I have elected to divide it into three units preferably of two stages of amplification each. The first unit 20 comprises in the present instance, a radio receiving assembly A and a microphone receiving assembly B, either of which may be cut in on the system by a switch device C. The second and third units of amplification 25 are each connected in circuit with the recording device D, but the third unit may be cut out upon occasion by the switch device E. The third unit is provided with kenetron or 30 rectifying tubes through which the system is served from a lighting or other similar circuit through wires F whereby the current is given a final and great increase. In Figure 2, my system is shown with the microphone assembly B including the primary amplifier 35 in circuit through the switch device C with the second amplifier, where the original current affected by the action of sound waves upon the microphone is again stepped up. Assuming now that the switch E is thrown to 40 place the second and third units of amplification in circuit; as the third unit is served from a lighting or other similar high powered circuit the desired increase of electrical energy is attained and delivered to my unique recording device D without loss in accuracy 45 or precision in the fluctuations of the current caused by the action of sound waves on the microphone. It will be manifest, therefore, that the principal advantage contemplated 50 by this phase of my invention resides in the preservation of the relative values of the minute fluctuations induced by the action of the sound waves on the original circuit of low amperage, and upon which the exact quantity 55 and timbre of the sound are dependent, during the process of amplification to develop sufficient electrical energy to afford the required power to record such fluctuations on a permanent and durable record. It has been 60 found impractical to record sound directly from a microphone for the reason that insufficient power is developed to cause the stylus to accurately record the overtones by which the quality and timbre of sound are 65 characterized. With my apparatus however,

it has been found that sufficient energy can be developed to actuate my unique cutting stylus with sufficient power to produce a record even upon a steel tape, and this without loss of the necessary sensitiveness required to accurately translate the overtones.

My recording device per se comprises a permanent magnet (1), preferably of the horseshoe type, the respective poles of which are designated N and S, and between these is 70 mounted by means of screws (3) a sectional, hollow soft iron pole pieces (4). The two sections X and Y (4) constitute the fields and are preferably identical in shape and size. Each pole piece is formed with a body (5) and flanges (6), on the ends of which are provided posts (7). When assembled, the pole pieces form a hollow compartment with the posts (7) opposed to each other and having their ends slightly spaced apart. Retained within the hollow portion of the pole pieces is a coil (8) formed with a central longitudinal opening (9) communicating medially of its length with a vertical opening (10) also formed therein. Extending through the longitudinal opening (9) in the coil is a 75 soft iron armature (11) which is hingedly mounted by a non-magnetic fitting (12) to one of the posts (7) of the pole pieces (4), with its free end extending some distance outwardly from the coil and between adjacent posts (7). There is sufficient clearance between the armature (11) and the walls of the opening (9) and ends of the posts (7) to permit limited movement of the armature, and the armature is normally held in a neutral intermediate position by non-magnetic S-shaped springs (13a) extending through the vertical opening (10) in the coil and mounted with their ends secured to the flanges (6) 80 of the sections of the core. Also mounted on the permanent magnet (1) by means of screws (14) are non-magnetic cover plates (15) carrying suitable binding posts (16) for the wire terminals (17) of the coil and the wire terminals (18) of the amplification system, so that when the system is in circuit with my recording device, the coil (8) is energized with a resultant polarization of the soft iron armature. However, the flow of current in the coil is not constant due to fluctuations therein resulting from the action of sound waves on the receiving device, thus the intensity of polarization of the armature (11) will manifestly vary thereby causing it to be alternately attracted toward the fields X and Y. Carried adjacent to the free end of the armature (11) is a depending rod (19) which extends through an opening provided in the lowermost cover plate (15) and into engagement with the stylus arm (20) which is thus given a movement corresponding to that of the armature. In order to regulate the movement of the armature (11) I have provided adjusting screws (21), the same being carried by the 85 90 95 100 105 110 115 120 125 130 135 140 145 150

respective cover plates (15), and each of these is formed with a head (22) carrying a felt pad (23) against the resistance of which the armature operates with a resulting limitation in the stroke thereof dependant upon the pressure exerted. Furthermore, it is manifest that more force is required to move the armature to affect cutting action upon a sound record than is required to relieve the cutting pressure, consequently to assure the application of greater power when working against the resistance of record material suitable adjustment may be made by screws (21) to move the armature nearer to the field Y and under a stronger magnetic influence. The screws are locked in position by screws (24). The effect of screwing down on the upper screw 21 in making the adjustment above described is to cause the upper pad 23 to be more compressed than the lower pad and the effect of the pads and the spring is to cause a dampening or cushioning action which compensates for the difference in force required to move the cutting point downwardly into the film and that required to raise it. By the combined effects of these instrumentalities it is possible to cut a symmetrical "hill and dale" sound groove in the film and thus avoid distortion of the record.

The stylus arm (20) is formed with a head (20a) provided with an opening through which extends a screw (25) for mounting the arm in a boxing (26) carried by the lower-most cover plate (15). The screw (25) is adjustable vertically through the medium of elongated slots (27) so that the angular relationship of stylus (28) may be regulated with respect to the record tape (29). It may be said here that the smoothness of the cut made by the stylus is dependant upon the angle at which the stylus is held against the record tape. The stylus head (20a) is further provided with a slot (30) through which a second adjusting screw (31) passes to hold the stylus arm in place, and a spring (32) seated in a recess (33) in the boxing functions to oppose any unsteadiness or displacement of the head.

The record tape (29) is fed from a suitable spool (not shown) across a support (34) to a reel or spool (35) which is actuated through the medium of suitable gearing (36) operatively connected with a power element (not shown), and a standard (37) is provided for supporting the permanent magnet (1) in the proper relationship to direct the stylus against the tape, the same is rendered detachable by means of a screw (38).

It will be apparent from the foregoing that when my system is placed in circuit with my recording device, that the armature (11) will be controlled in its movement by the fluctuations in the current affected by sound waves acting either upon the microphone or radio receiving set, and that such movements

will be duly transmitted to the stylus (28) through the stylus arm (20) and rod (19), and that an accurate and precise record will be made upon the tape (29), it being assumed that the tape is actuated to move across the standard (34). However, it is also desired to emphasize the fact that by re-arrangement of the armature with respect to the coil, field and permanent magnet, that the fluctuations in current caused by sound waves may be recorded by furrows on the record possessing either vertical or horizontal irregularities.

While in the foregoing there has been illustrated and described such combination and arrangement of elements as constitute the preferred embodiment of my invention, it is nevertheless desired to emphasize the fact that interpretation of the invention should only be conclusive when made in the light of the subjoined claims.

Having described my invention and its objects with such attention to detail as will thoroughly acquaint one skilled in the art with its construction and advantages, I claim:

1. A sound recording device comprising an armature associated with an electrical device sensitive to fluctuations in current induced by sound waves, a stylus arm formed with a slot therein and arranged to be actuated by said armature, adjustable pivoting means for said stylus arm, inherently resilient means for resisting adjustment of said pivoting means in one direction, and adjusting means extending through the slot in the stylus for positively supporting said pivoting means and adapted to regulate the position of said pivoting means against the resistance of said inherently resilient means.

2. A sound recording device comprising an armature associated with an electrical device sensitive to fluctuations in current induced by sound waves, a stylus arm formed with a slot therein and arranged to be actuated by said armature, a boxing provided with slots, pivoting means for said stylus arm carried by the boxing and adjustably mounted in the slots therein, a spring in said boxing for resisting adjustment of said pivoting means, and manually adjustable means extending through the slot in the stylus for supporting said pivoting means and adapted to regulate the position of said pivoting means against the resistance of said spring.

3. A device for recording the fluctuations in an electrical current comprising a permanent magnet, a core carried by the magnet, a coil within the core and connected with the electrical circuit for polarizing the core, said coil being provided with intercommunicating openings, an armature carried in one of said openings, and inherently resilient supporting means for the armature carried in

the other of said openings and attached to the core.

4. A sound recording device comprising an armature and a coil in an electro-magnetic field in circuit with a source of electrical energy sensitive to sound waves, said armature being pivoted at a point without a coil, and additional means extending through the coil for supporting the armature at a point intermediate its length for the purpose defined.

5. A sound recording device comprising an electro-magnetic field in circuit with a source of electrical energy sensitive to sound waves, an armature and a coil included in said field, and the armature being arranged to extend through the coil, means for pivotally supporting the armature at a point without the coil, means for supporting said armature at a point within the coil, and adjustable means adapted to engage said armature at a point removed from the pivoting means for regulating the vibrations of said armature for the purpose defined.

6. A device for recording the fluctuations in an electrical current comprising a permanent magnet, a sectional core carried by the magnet, a coil within the core and connected with the electrical circuit for polarizing the core, said coil being provided with vertical and longitudinal communicating openings therethrough, an armature carried in one of said openings, and spring means carried in the other of said openings and attached to the core for supporting the armature.

7. A sound recording device comprising a coil connected with a source of electrical energy sensitive to sound waves, said coil being provided with vertical and longitudinal communicating openings therethrough, a core surrounding the coil, a permanent magnet associated with the core, an armature carried in one of the openings in the core, spring means for supporting the armature extending through the other opening in the coil and attached to the core, and means for adjusting the armature for the purpose defined.

8. A sound recording device comprising a stylus arm, a stylus carried by the arm, said stylus arm, a stylus carried by the arm, said 50 ing an opening and a slot therein communicating with the opening, a housing for the head, adjustable means engaged with the head through the opening therein, said means being carried in a slot formed in the housing, adjustable means carried by the housing and extending within the slot in the head for raising and lowering the head, and a spring device within the housing and engaging the head and exerting its pressure in opposition to the aforementioned adjustable means for the purpose defined.

9. In a device for generating speech current from a sound record, the combination 60 of means for creating a steady magnetic field,

opposing pole pieces in the magnetic circuit and spaced apart to form an airgap, an armature in the airgap, a support for said armature, resilient stops between the armature and pole pieces for controlling the movement of said armature, and means for operatively connecting said armature with a sound record.

10. In a device of the character described, means creating a steady magnetic field, 75 opposing pole pieces in the magnetic circuit and spaced apart to form an air gap, an armature in the air gap and arranged to move toward and from the pole pieces, damping means directly engaging and controlling the movement of said armature throughout its entire range of movement, and means for operatively connecting said armature with a member capable of carrying a sound record.

11. A device for recording electrical 80 fluctuations comprising a permanent magnet, a sectional core carried by said magnet, a coil within the core provided with a longitudinal opening, an armature pivoted in said opening and means for normally positioning said armature said means consisting of a reversely curved non-magnetic spring connected at its center to the armature and at its ends to the core.

12. A sound recorder adapted for cutting 85 a hill and dale record in relatively hard material such as a photographic film, the combination of a cutting stylus, means for creating a magnetic field, means for substantially varying said field in accordance with 100 sound to be recorded, an armature, means for biasing said armature to a position in said field and means for resisting the movement of said armature from said position, said means being more effective on displacement of said armature in one direction than on displacement of said armature in the opposite direction.

13. A sound recorder adapted for cutting a hill and dale record in relatively hard material such as a photographic film, the combination of a cutting stylus, means for creating a magnetic field, means for substantially varying said field in accordance with 115 sound to be recorded, an armature, means for biasing said armature to a position in said field and damping pads for resisting movements of said armature in opposite directions respectively, one of said pads offering greater resistance to movement of said 120 armature than the other.

14. A sound recorder adapted for cutting a hill and dale record in relatively hard material such as a photographic film, the combination of a cutting stylus, means for creating a magnetic field, means for substantially varying said field in accordance with 125 sound to be recorded, an armature, means for biasing said armature to a position in said field, means for applying greater force to 130

said armature when said armature is displaced in one direction from said position than when displaced in the opposite direction from said position.

5 15. The method of cutting a hill and dale sound groove in relatively hard material such as the usual motion picture film by means of a cutting stylus operatively connected to an armature which operates between the poles 10 of an electrical magnet and is connected to the armature by linkage having a leverage of at least substantial unity, which method consists in normally biasing said armature to position closer to one pole than to another, 15 energizing said magnet by current which varies in accordance with the sound to be recorded, whereby said stylus is operated more strongly for displacement into the film than for displacement in the opposite direction, 20 damping the movement of said stylus in both directions and drawing the film against said stylus.

16. The method of cutting a hill and dale sound groove in relatively hard material such 25 as the usual motion picture film by means of a cutting stylus operatively connected to an armature which operates between the poles of an electro-magnet and is connected to the armature by means having a leverage of at least substantial unity, which method consists in normally biasing said armature to position closer to one pole than to another and energizing said magnet by current which is 30 subject to relatively large variations in accordance with sound to be recorded, whereby said stylus is operated more strongly for displacement into the film than for displacement in the opposite direction, damping the movement of said stylus in both directions and 35 drawing the film against said stylus.

17. The method of cutting a hill and dale sound groove in relatively hard material such as the usual motion picture film by means of a cutting stylus operatively connected to an 40 armature which operates between the poles of an electro-magnet and is connected to the armature by linkage having a leverage of at least substantial unit, which method consists in normally biasing said armature to 45 position closer to one pole than to another, energizing said magnet by current which varies in accordance with the sound to be recorded, whereby said stylus is operated more strongly for displacement into the film 50 than for displacement in the opposite direction, damping the movement of said stylus in both directions and drawing the film against said stylus at an acute angle thereto.

55 18. In a device of the class described, a 60 permanent horseshoe magnet, pole pieces positioned between the ends of said magnet and forming two pairs of opposed poles, a coil enclosed by said pole pieces, a straight armature pivotally supported by and at one pair 65 of poles, said armature extending through

the coil and between the other pair of poles, an operating connection between the armature and sound record, cover means at opposite sides of said magnet closing the opening between the legs of the magnet and extending beyond the magnet and means for biasing said armature to a position between the poles and for damping the motion thereof, said last named means being partly supported by said pole pieces and partly by said cover 70 means.

75 19. In a device for recording sound, means creating a permanent magnetic field, opposed pole pieces, a pivotally mounted armature movable near one end between said pole pieces, a cutting stylus, a pivotally mounted arm supporting said stylus, an operating connection between said armature and stylus connected to said armature adjacent said pole pieces, the leverage between said armature and stylus being at least substantial unity, and damping pads engaging opposite sides of one end of said armature at a point distant 80 from its pivotal support.

85 In testimony whereof I affix my signature 90 hereunto.

EARL H. FOLEY.
